COMBINED FLUID AND ROTARY DRIVEN
DRILLING BIT

John A. Zublin, Los Angeles, Calif.

Application July 15, 1938, Serial No. 219,357

15 Claims. (Cl. 255—71)

This invention relates to drilling tools, and more particularly to tools used in the rotary drilling of bore holes, such as oil wells.

It is an object of this invention to provide a drilling bit in which only a portion of the energy required to operate the bit is furnished through the customary rotation of the drill pipe.

Another object of this invention is to provide a drilling bit in which additional energy to rotate the bit is furnished by fluid under pressure flowing through the drill pipe.

A further object of the invention lies in the provision of an improved drilling tool operable by fluid pressure, the drilling tool being in the nature of a water wheel or turbine.

Still another object of the invention involves a drilling bit having its cutting elements rotatable by the direct or indirect application of drilling fluid acting upon them.

Another object of the invention is to rotate the cutting elements of a drilling bit by the direct effect of drilling fluid acting upon them, which fluid substantially simultaneously cleans the teeth, the bit and the hole bottom.

Still a further object of the invention is to provide a turbine type of drilling tool that can operate against a minimum amount of back pressure, thereby increasing its efficiency of operation.

A further object of the invention involves a multiple jet turbine type of drilling bit in which the reactive force of the jets neutralize one another.

Yet another object of the invention lies in the provision of drilling tools in which the cutters are rotated by means of fluid, the bearing loads imposed on the cutters by the formation being counteracted by the action of the fluid on the cutters.

A further object of the invention is to provide a drilling tool capable of producing a bore hole by the combined action of rotation of the drill pipe and fluid under pressure causing roller cutters to rotate.

This invention possesses many other advantages and has other objects that will become apparent from a consideration of one or more embodiments of the invention. For this purpose, several forms are shown in the drawings accompanying and forming part of the present specification, which embodiments will now be described in detail, illustrating the general principles of the invention. However, it is to be understood that this detailed description is not

to be taken in a limited sense, since the scope of the invention is best defined by the appended claims.

Referring to the drawings:

Figure 1 is a partially longitudinal sectional view of one form of the invention.

Figure 2 is a longitudinal section taken generally along the plane 2—2 in Figure 1.

Figure 3 is a fragmentary section showing the manner of assembling the bearing balls in the main bearing raceways.

Figure 4 is a partially longitudinal sectional view of another embodiment of the invention.

Figure 5 is a partially sectional view taken along the line 4—4 of Figure 3.

Figure 6 is an elevation of part of the turbine cutter assembly disclosed in Figures 4 and 5.

Figure 7 is a section taken along the line 7—7 of Figure 4; and

Figure 8 is a perspective view on an enlarged scale of one of the buttons used in connection with the main bearing.

In its general aspects, the present invention utilizes the energy in fluid under pressure forced through the drill pipe for rotating the rotary cutting elements of a bit, relying upon the reaction of the cutters upon the formation to produce a rotation of a supporting member for the cutters, whether it be a shank, or a wheel or carrier of the nature described in my Patents

Nos. 2,050,988, 2,050,989 and 2,119,618. In situations where the cutters are mounted directly upon the shank, the circulating fluid will be caused to issue through holes, nozzles or channels to strike upon blades, buckets or other vanes forming part of or attached to each roller cutter; or the fluid stream can be caused to impinge directly upon the cutter teeth or elements themselves.

By utilizing the energy in the circulating fluid, not only can the cutters be turned and the proper bore hole size produced, but the same fluid exiting the cutters will keep the teeth clean and also the bottom of the hole.

The contemplated drilling bits avoid the necessity for transmitting the entire energy required for removing the formation through the drill pipe, inasmuch as utilization is made of the energy in the circulating fluid for turning the cutting elements, which is independent of rotation of the drill pipe. However, in the embodiments

of my invention disclosed in the drawings, it is preferable that the major cutting effort be produced by utilizing the energy in the fluid under pressure, but the drill pipe still be rotated at a moderate speed to insure that all parts of the

15

30

35

40

45

50

55

bore are covered to produce a round hole of the diameter desired, such rotation also insuring that the drill pipe, which serves as a conduit for the fluid, will not become stuck in the bore.

5 In the form of invention illustrated in Figures 1 and 2, a shank 10 is provided having a tapered threaded pin 11 for attachment of the bit to the usual string of drill pipe (not shown). The shank possesses two depending legs 12, 13 between which are carried the fluid operated water wheel or turbine cutting portions of the bit. Such cutting portions include a wheel or carrier 14 rotatably mounted upon a bearing support or sleeve 15, preferably through the agency of balls 16 rollable in the respective toric raceways 17, 18 provided on the exterior of the sleeve 15 and the interior of the wheel or carrier 14. The sleeve is carried by the legs by being received at one end in the bore 19 provided in one of the legs 12, with its other end being receivable in a bore or recess 20 provided in the other leg 13. Rigid attachment of the sleeve to the legs is obtained by piloting the reduced extension 15a on the end of the sleeve in the recess 20 and by providing the taper or bevel 21 in the inner portion of the leg 13 for the reception of welding material 22 functionally integrating the sleeve to the leg. The other end of the sleeve is rigidly secured to the other leg 12 by means of the welding material 23 fused to the sides of the leg bore 19, the end of the sleeve 15 and the outer surface of a plug 24 threadedly received within the sleeve. This plug is provided in order to obtain a greater welded surface, and consequently a greater extent of attachment of the sleeve to the leg and shank.

40 A plurality of cutters 25 is rotatably mounted on the wheel or carrier 14, being spaced circumferentially therearound, each cutter being rotatable upon a bearing pin 26 receivable in aligned bores or holes 27 provided in the end walls 28, 29 of the wheel. Each pin is rigidly affixed to the wheel by welding in material 30 in the bores 27. The individual rollers rotate within recesses 31 45 in the wheel or carrier defined by the webs or ribs 32 integral with the walls 28, 29 of the wheel and extending therebetween. The web and pins cooperate to produce rigidity in the spaced walls of the wheel.

50 The parts described can be assembled by inserting each roller 25 in its recess 31 and placing its bearing pin 26 through the roller and holes 27 in the walls of the wheel, after which the end welds 30 can be provided. The wheel with the 55 rollers assembled thereto can then be inserted between the legs 12, 13 and the sleeve 15 placed through the bore 19 in the leg 12, through the inner raceway in the carrier, until the reduced end portion 15a of the sleeve is piloted in the bore 20 in the other leg 13. The sleeve can then be welded to the leg by welding in the tapered groove 21 provided between the leg and the sleeve. Thereafter, the balls 16 can be inserted into the respective raceways 17, 18 through the 60 bores 33 extending inwardly through the end faces of the carrier. With the raceways filled with the required number of balls, a plug 34 can be inserted into each of the bores and suitably attached thereto, as by welding. Each plug 34 65 will have preferably a curved surface for each raceway, the curvature being such as to provide continuity in the rolling of the bearing balls 16 on the inner portions of the carrier. The end plug 24 can now be threaded into the sleeve 15, and the groove between the leg, sleeve and plug

70 filled in with welding material 23, as aforementioned.

The general assembly described is similar in many respects to the types of drilling tools disclosed in the aforementioned patents. However, 75 there are essential differences both in construction and mode of operation, which will now be indicated.

It is desired to rotate the cutters and their carriers by the action of fluid acting directly upon them. For this purpose, the sleeve 15 has extending at spaced intervals around its periphery a plurality of nozzles or orifices 35, 36. For the purpose of economy in manufacture, it is preferred to form the sleeve from several parts, including two annular end portions 15b, 15b, held together by the annular ring 15c of welding material through which the nozzles 35, 36 extend and in which they are rigidly secured. One mode of assembling the nozzles includes placing them 20 in proper angular and circumferential position on a suitable fixture, such as a copper plate, and depositing welding material 15c therearound to form an annulus. This annulus of welding material carrying the nozzles is then welded to the 25 end portions 15b, 15b, forming a functionally integral sleeve with the nozzles in proper assembled position.

The nozzles are positioned to direct jets of fluid, such as drilling fluid, on to both the carrier 30 14 and teeth 25a of the cutters to produce their rotation. The carrier is provided with spaced openings 37 defined by the webs or ribs 32. The leading side of the opening is shaped to simulate a turbine blade 38 so as to be capable of guiding 35 and directing a fluid stream issuing from a nozzle on to the cutter teeth 25a spaced around the periphery of each roller cutter 25.

In order to convey the fluid to the sleeve 15, the shank is provided with a passageway 39 40 which will communicate with the string of drill pipe and also with the sleeve. Fluid under pressure will enter the sleeve through the passageway and will have its pressure head changed to kinetic or velocity head as it passes through the discharge nozzles 35, 36. The fluid stream will strike against the wheel blades 38, imparting some of its energy thereto to rotate the wheel on its ball bearings 16. However, only part of the energy will be consumed in such rotation, the 50 fluid being guided by those blades, in a similar manner to stationary guide blades in a turbine, and will impinge upon the teeth 25a of each cutter to cause its rotation on its bearing pin 26.

It will be noted that about one-half of the cutters are in contact with the bottom of the hole. The turning effort imposed upon each of these cutters under the impetus of the fluid stream issuing through the nozzles will force the carrier or wheel 14 to rotate, in view of the gearing effect of the teeth with the formation, causing the cutters to roll or walk along the formation and thereby carry the wheel with them, in a manner similar to the turning imposed upon a carrier by the engagement of rotating planet pinions with a stationary orbit gear. By virtue of the rotation of the carrier 14 on the bearing sleeve 15 caused by the fluid engaging the cutter teeth 25a and its direct action upon the carrier blades 38, the cutters will be brought intermittently into 60 and out of contact with the hemispherical hole bottom to achieve the functions mentioned in my aforementioned patents. Because of this mode of operation, only about one-half of the cutters will be in formation contact at any one 70 75

time, the remaining cutters being "in reserve."

The cutters 25 will remove the formation by virtue of their contact with the bottom of the hole, tending to produce a bottom of semi-circular longitudinal section, equal in width to the length of the cutters. For the purpose of producing a hemispherical hole bottom, and consequently, a round bore of the required diameter, the shank is also rotated by turning the drill pipe, which will cause the carrier or wheel and the rollers to assume an infinite number of planes of rotation and produce a similar number of semi-circular sections, all of them combining to produce a hemisphere.

15 By the present invention, many disadvantages associated with other methods of rotary drilling bore holes are overcome. The equipment now used consists of a rotary table and associated driving mechanism at the surface of the hole, 20 and a bit at the bottom of the hole, the motion of the table being conveyed to the bit through a string of drill pipe serving as a power transmitter. Because of this arrangement of parts, the entire torque necessary to turn the bit must be transmitted through the drill pipe and its threaded 25 joints, which must be of ample thickness and size to withstand the twisting stresses imposed upon them. This thickness in size must be further increased to enable the drill pipe to support its 30 own weight in tension, due to the necessity for the cable mechanism at the surface of the hole to take weight off the bit and prevent buckling of the entire drilling string. Paradoxically, this heavy drill pipe section increases the entire tension 35 of the string, the pipe required for deep well drilling of the nature of 9,000, 12,000 and 15,000 feet being of such heavy section that its maintenance in tension strains its joints almost to the yield point.

40 This invention overcomes the difficulty noted. The cutting action can take place at a more rapid rate than is obtainable through transmission of the entire energy through rotation of the drill pipe. The twisting effort on the drill pipe will be 45 relatively small, since the main cutting effect occurs under the influence of the fluid streams issuing through the openings of the carrier, the rotation of the drill pipe only insuring that a proper hole size and shape will be produced. In 50 view of the lesser torque transmittable through the drilling string, each stand of pipe can be made much lighter. Furthermore, the more rapid rate at which the cutters are turned under the impetus of the fluid stream permits the use of lighter 55 drilling weights, relieving the strain on the equipment and also resulting in the production of a straight hole.

I am aware that it has been proposed to utilize the energy in a stream of fluid for rotating a 60 drilling bit by placing a long, multi-stage turbine near the lower end of a string of drill pipe, the driven end of the turbine being coupled to the shank of the usual bit for rotating it at a rapid speed. Such arrangements possess the disadvantage 65 that the turbines are susceptible to extreme wear caused by the heavy drilling fluid, and they must also operate against a very high back pressure produced by the necessity for keeping the bit and the hole clean through the fluid issuing 70 through the usual nozzles presently incorporated in rotary drilling bits. Manifestly, the use of such high back pressures decreases the efficiency 75 of the turbine unit. Moreover, there is substantially no advantage in the use of such turbine combinations insofar as the drill pipe and joints

are concerned. The drilling string must still support its own weight in tension; and it still has the entire drilling torque imposed upon it since the reactive torque upon the stator of the turbine unit will be transmitted to the drill pipe 5 to which it is connected. Consequently, the drill pipe and joints must be made of as heavy sections as are required when the drilling string is used as a power transmitter between the rotary table at the surface of the hole and the drilling 10 bit.

As distinguished from this latter combination of mechanisms, the present invention incorporates a turbine directly into the drilling bit, there being no need for operating against high back 15 pressures, since the fluid exhausting from the cutting teeth 25a into the hole has imparted its available energy towards rotating the carrier and cutters. Nor is there any reactive torque imposed upon the string of drill pipe. It will be noted 20 that the nozzle holes are positioned to rotate the cutters and wheels about axes substantially at right angles to the axis of the drilling string. Consequently, there is practically no reactive torque on the drill pipe. What reaction is present 25 is practically neutralized in the drill bit itself because of the disposition of the nozzle holes around the axis A—A of the carrier, the reactive forces of the streams issuing from the nozzle holes one half of the sleeve being substantially 30 counterbalanced by the reactive force of the opposite grouping of nozzles. This non-transmittal of torque permits the use of lighter drill pipe, which decreases the tension in the 35 drilling string.

It will be noted that the fluid acting upon the cutter teeth not only urges their rotation together with the wheel or carrier, but also thoroughly effects their cleaning. The fluid leaving the formation contacting cutters will pass to the bottom 40 of the hole, removing the cuttings therefrom and carrying them upwardly around the drill bit. Thus, separate cleaning nozzles are not necessary in this form of bit, eliminating the need for operation against higher back pressures than are 45 present in the bottom of the hole.

In the type of bit just described, only the lower half of the cutters in contact with the formation have loads imposed upon them. Those in the upper half are out of contact and are therefore 50 free to turn without restraint. If the same extent of fluid stream were permitted to issue through the nozzles and strike the cutter teeth when the rollers were in their upper position, they would be rotated at extremely rapid speeds, 55 which motion would produce no useful function. Accordingly, although not essential, the nozzles 36 in the upper portion of the sleeve have a much smaller cross-sectional area than the nozzles 35 acting against the carrier and rollers that are in 60 the lower position. These upper nozzles 36 will also strike against the side blades 38 of the wheel to assist in its rotation, the fluid leaving these blades and acting upon the cutter teeth 25a to 65 rotate the cutters and insure their thorough cleansing by removing whatever matter has not been displaced while they were in formation contact. By decreasing the upper nozzle area the cutters out of formation contact will not be rotated too rapidly, and will therefore be possessed 70 of a longer effective life.

If deemed essential, the upper nozzles 36 can be eliminated and the fluid stream be prevented from acting upon the cutters that are out of formation contact, the rotation of the carrier 75

successively moving the cutters back into formation contact where they will again be acted upon by the fluid jet issuing from the lower nozzles of larger cross-sectional area.

5 As stated above, the wheel blades 38 are so designed that the stream issuing from each nozzle will engage against them to impart only part of their energy thereto in causing carrier rotation. The fluid leaving the wheel blades will still have 10 a high percentage of its kinetic energy remaining, the exiting portions of each wheel blade being so designed as to direct the jet materially inwardly of the outer end of each tooth 25a. This design is preferred since wearing down or 15 blunting of the cutter teeth incident to their digging into the formation will not permit the fluid to pass them by, the fluid stream being effective during the entire life of the drilling tool.

It will be noted that each cutter has a close 20 fit with the curved portion 31a of its confining recess to keep windage losses and eddying to a minimum. It will be noted further that the fluid acting somewhat inwardly on the cutting teeth tends to resist centrifugal action trying to throw 25 it outwardly. The inward thrust of the fluid also counterbalances the reactive force of the formation upon the cutter teeth, thereby decreasing the bearing loads imposed by each cutter upon its bearing pin 26 and adding to the effective life of 30 the drilling bit as a whole.

Tracing through a cycle of operation of a cutter beginning with its position as it moves into formation contact, the fluid will issue from one of the nozzles 35, striking against the bucket or 35 blade 38 on the wheel or carrier, which will guide it on to the cutting teeth 25a, causing the rolling of the cutter on the formation in the manner aforementioned to carry the wheel along with it and produce its rotation on its main bearing 40. As the wheel rotates in a clockwise direction, as seen in Figure 2, the stream issuing from the jet will pass directly through the wheel opening 37 without engaging the carrier blade 38, its full force being expended against the teeth 45 of the cutters, which will function as water wheel buckets or turbine blades, the cutter being further rotated and carrying the carrier with it. As the carrier continues to rotate, the fluid stream will engage against the back portion 38a of the wheel opening, from where it will be deflected against the cutter teeth in the proper 50 direction for continuing rotation of the cutter 25. From this position, the cutter will pass successively under the influence of the other nozzles 55 35, where the operation just described will be repeated, until the cutter comes out of formation contact, after which it will be cleansed by the smaller jets issuing from the upper nozzles 36 of lesser cross-section.

60 In the specific form disclosed in the drawings, the axis of rotation A—A of the wheel or carrier is inclined to the horizontal. Such inclination permits the incorporation of a properly designed flow channel 39 in the shank leg 13 in view 65 of the greater amount of shank material that can be placed on that portion of the shank. With this inclination, the cutters engage the bottommost portion of the hole almost entirely to one side of the hole axis B—B to avoid dead centers, but nevertheless overlap the hole axis to a slight extent to insure that all parts of the formation will be covered by the cutting teeth in cooperation with the rotation of the tool through the agency of the string of drill pipe.

70 In the forms of invention illustrated, the drill

75 pipe is rotated at a moderate speed so that the cutters cover all parts of the hole bottom. Such rotation is taken advantage of by offsetting the tapered pin 11 on the upper end of the shank with respect to the hole axis B—B to make available the effects of centrifugal force incident to eccentric rotation of a drill collar, as explained in my Patent No. 2,119,619, by virtue of which an undersized bore is prevented as wear occurs on the cutter teeth and other parts.

10 The number of rollers 25 spaced around the carrier is preferably an odd number, to avoid flat spots. While seven rollers are shown in the figures, it is to be understood that the invention is not limited to that number, those used being 15 dependent upon the design of the cutters and the size of the tool. It will be further appreciated that the cutter teeth can assume various other shapes than that disclosed and have various inclinations.

20 The form of invention shown in Figures 4 to 8, inclusive, operates in a manner similar to the first described embodiment. That is, the major cutting and turning effort on a cutter mechanism is exerted by a fluid stream, assurance 25 being had that all parts of the hole are covered by supplementing this effort through rotation of a string of drill pipe and shank of the tool connected thereto.

25 The drill bit includes a plurality of depending 30 legs 40, 41 extending from the shank body 42, the upper end of which carries the usual threaded pin 43 for connecting the bit with the string of drill pipe (not shown). One of the legs 40 has formed integrally therewith a bearing supporting member 44 adapted to carry a cutter assembly 45, to be described hereinafter. The end of the bearing supporting member is provided with a reduced extension 44a fitting into a bore 46 formed in the leg 41 of the shank 42, 35 which leg, after the cutter assembly has been placed on the bearing supporting member, can be welded at its upper end 41a to the shank body proper 42 and at its lower region 41b to the reduced extension. The cutter assembly 45 includes a cutter carrier 46 provided with a plurality of circumferentially spaced cutter teeth 47 to be described in detail hereinafter. The carrier 46 is provided with a plurality of ball bearing raceways 48 in an inner bore, which are adapted to cooperate with an inner bearing race 49 containing complementary toric raceways 50. Between the raceways are placed balls 51 which will serve to transmit bearing loads between the carrier and inner race.

50 Prior to the placing of the separate long leg 55 41 on the reduced bearing extension 44a and its welding thereto and to the shank body, the carrier 46 is placed over the inner race 49 and the bearing balls 51 introduced into the raceways 48, 50 through the holes 52 formed within the inner race and communicating with respective raceways. Thereafter, buttons 53 having an upper cylindrical portion 53a and a lower rectangular portion 53b are inserted into the bores, serving to prevent the balls from falling from the raceway while at the same time providing a substantially continuous raceway on which the balls can roll as the carrier rotates. The lowermost portion of the buttons is made rectangular in shape 65 so as to be capable of riding in the keyway 54 formed in the bearing supporting member 44, and thus serving to lock the inner race 49 from rotation with respect to the bearing supporting member. As explained in my application en- 70 75

tilled Compact bits, filed February 21, 1938, Serial No. 191,622, in which the bearing and shank construction is being claimed, the buttons 53 serve the three-fold function of providing a substantially continuous raceway, preventing the balls from falling from the raceway, and keying the inner raceway to the bearing supporting member.

Upon assembly of the carrier 46 on the main bearing 49 and the insertion of the balls 51 in the manner aforementioned, this entire assembly is slid over the bearing supporting member 44 with the rectangular button heads 53b riding in the keyway 54. Thereafter, the long leg 41 is placed over the reduced extension 44a with the boss 55 on the leg abutting the end 56 of the inner race 48, and causing the opposite end 57 of the race to abut the boss 58 formed on the other shank leg 40. Upon welding the upper part 41a of the leg to the shank and the lower part 41b to the reduced extension, a rigid shank assembly results for carrying the cutter assembly 45 for rotation with respect to the shank about a preferably inclined axis C-C with the bottommost cutter teeth 47 positioned mainly to one side of the axis D-D of the hole, in a similar manner to the inclined positioning of the carrier 14 described in connection with the Figure 1 and 2 embodiment.

As described in my copending application, the cuttings are removed from the bottom of the hole by discharge of fluid from a nozzle 59 threadedly held in the lower portion of the short leg 40, which has a conduit 60 therein for establishing communication between the shank passageway 61 and the nozzle. The fluid will issue from this lower nozzle and sweep transversely across the hole bottom for effectively removing the detritus.

The upper portion 42a of the shank adjacent the periphery of the cutter teeth 47 is positioned closely adjacent the ends of the teeth, embracing a material angular distance of the carrier circumference. A fluid channel 62 is provided in the upper shank portion, communicating with the fluid passageway 61 and terminating at the embracing shank portion 42a adjacent the periphery of the cutting teeth. A separate or integral nozzle 63 can be incorporated in this channel, being so placed on the shank as to direct its discharge against the teeth 47 of the wheel carrier to cause its rotation on its bearing by virtue of the kinetic energy in the fluid stream, in much the same manner as a nozzle can direct a stream of fluid or liquid against the buckets or blades of a water wheel to cause its rotation.

The wheel 46 will be rotated through the action of the fluid stream issuing from the nozzle to remove the formation, producing a substantially semicircular hole bottom in longitudinal section equal in width to the distance across the cutter teeth 47. As described in connection with the Figure 1 and 2 specie, the shank will be rotated through the usual string of drill pipe to cause the carrier 46 and its cutting teeth 47 to assume an infinite number of rotational positions and thereby produce a hemispherical hole bottom with a bore of the required diameter.

Although the cutter teeth 47 can assume various shapes, it is preferred to form them in a manner similar to the buckets on a water wheel. For this purpose, each tooth or blade 47 is formed with two bucket sections 47a, 47b symmetrically disposed about the central rotational plane of the wheel or carrier, each bucket presenting a con-

cave face to the action of the fluid stream leaving the nozzle, with the back faces of the buckets being preferably convex. The center line of the nozzle is so placed as to intersect the central plane of the carrier, in order that the fluid stream issuing therefrom will be directed against the buckets, striking them at the central plane where it will be divided and deflected therealong towards the sides of the blades or wheel. The nozzle is inclined at a proper angle so that the fluid issuing therefrom can strike successive blades and impart its kinetic energy thereto to cause rotation of the wheel and the digging of the hole, as described above. Sufficient clearance is allowed between the ends of the blades or teeth and the legs 40, 41 of the shank to prevent any obstructions to the flow of fluid from the teeth and decrease the back pressure to that present at the bottom of the hole.

The arrangement described will resist the centrifugal action tending to throw the fluid outwardly since the direction of the stream is partially downwardly into the wheel or carrier. This will eliminate interference between entering and exiting fluids. The downward direction of the fluid stream will also relieve the formation thrust on the cutters from being communicated to the bearings by virtue of its partial counteracting effect on such reactive forces.

I claim:

1. In an earth boring apparatus, a shank, a carrier, means rotatably mounting said carrier on the shank, and a plurality of cutters rotatably mounted on said carrier, and fluid discharge means supported by said shank, said means being within said carrier and adapted to direct its discharge against the cutters and cause their rotation.

2. In an earth boring apparatus, a shank, a carrier, means rotatably mounting said carrier on the shank, a plurality of cutters rotatably mounted on said carrier, and fluid discharge means co-operable with said shank and arranged to direct its discharge against those cutters in formation contact in a direction to induce rotation with respect to the carrier, and by their reaction on the formation produce rotation of the carrier on the shank.

3. In an earth boring apparatus, a shank, a carrier, means rotatably mounting said carrier on the shank, a plurality of cutters rotatably mounted on said carrier, and fluid discharge means supported by said shank, said means being within said carrier and adapted to direct its discharge against the carrier and cause its rotation.

4. In an earth boring apparatus, a shank, a carrier, means rotatably mounting said carrier on the shank, a plurality of cutters rotatably mounted on said carrier, and fluid discharge means supported by said shank, said means being within said carrier and adapted to direct its discharge against the carrier and cutters to cause their rotation.

5. In an earth boring apparatus, a shank, a carrier, means rotatably mounting said carrier on the shank, a plurality of cutters rotatably mounted on said carrier, and fluid discharge means co-operable with said shank and arranged to direct its discharge against the carrier and those cutters in formation contact, whereby to produce their rotation with respect to the carrier.

6. In an earth boring apparatus, a shank, a carrier rotatably mounted on the shank, cutter means rotatably mounted on said carrier, and

fluid discharge means cooperable with said shank and positioned closely adjacent one or more of said cutters in formation contact, whereby to direct its discharge against said cutter means and produce rotation of said cutter means with respect to said carrier, and of said carrier with respect to the shank.

7. In an earth boring apparatus, a shank adapted to rotate about the axis of the bore being produced, a carrier rotatably mounted on the shank about an axis transversely of the bore, cutter means rotatably mounted on said carrier, and fluid discharge means cooperable with said shank and positioned closely adjacent one or more of said cutters in formation contact, whereby to direct its discharge against said cutter means and produce rotation of said cutter means with respect to said carrier, and of said carrier about said transverse axis.

20 8. An earth boring tool comprising a shank carrying a bearing support, a carrier rotatably mounted on said bearing support, a plurality of cutters rotatably mounted on said carrier, a fluid passageway in said shank, a fluid passageway in said bearing support communicating with said shank passageway, and one or more fluid discharge means communicating with said bearing passageway and arranged to direct its discharge against said cutters to cause their rotation.

30 9. An earth boring tool comprising a shank carrying a bearing support, a carrier rotatably mounted on said bearing support, a plurality of cutters rotatably mounted on said carrier, a fluid passageway in said shank, a fluid passageway in said bearing support communicating with said shank passageway, and one or more fluid discharge means extending through said bearing support to its passageway and arranged therein to direct its discharge against said carrier.

40 10. An earth boring tool comprising a shank carrying a bearing support, a carrier rotatably mounted on said bearing support, a plurality of cutters rotatably mounted on said carrier, a fluid passageway in said shank, a fluid passageway in said bearing support communicating with said shank passageway, and a plurality of nozzles spaced around said bearing support and extending therethrough to its passageway, said nozzles being arranged to direct their discharge against said cutters to cause their rotation.

50 11. An earth boring tool comprising a shank carrying a bearing support, a carrier rotatably mounted on said bearing support, a plurality of cutters rotatably mounted on said carrier, a fluid

passageway in said shank, a fluid passageway in said bearing support communicating with said shank passageway, and a plurality of nozzles spaced around said bearing support and extending therethrough to its passageway, said nozzles being arranged to direct their discharges against said carrier to cause its rotation.

12. An earth boring tool comprising a shank carrying a bearing support, a carrier rotatably mounted on said bearing support, a plurality of cutters rotatably mounted on said carrier, a fluid passageway in said shank, a fluid passageway in said bearing support communicating with said shank passageway, fluid discharge means extending through said bearing support to its passageway, and blades on said carrier, said discharge means being arranged to direct its discharge against said carrier blades to produce rotation of the carrier.

20 13. An earth boring tool comprising a shank carrying a bearing support, a carrier rotatably mounted on said bearing support, a plurality of cutters rotatably mounted on said carrier, a fluid passageway in said shank, a fluid passageway in said bearing support communicating with said shank passageway, fluid discharge means extending through said bearing support to its passageway, and blades on said carrier, said discharge means being arranged to direct its discharge against said carrier blades, and said blades being so shaped as to guide and deflect said discharge against said cutters, whereby to produce rotation of said carrier and cutters.

30 14. An earth boring tool comprising a shank carrying a bearing support, a carrier rotatably mounted on said bearing support about an axis, a plurality of cutters mounted in recesses spaced around said carrier, a fluid passageway in said shank, a fluid passageway in said bearing support communicating with said shank passageway, fluid discharge means extending through said bearing support to its passageway, means including blades defining openings in said carrier communicating with said recesses, fluid discharge means extending through said bearing support to its passageway, said discharge means being arranged to direct its discharge through said opening for direct action upon said cutters and also against said blades.

40 15. An earth boring tool as defined in claim 14, the rotational axes of said cutters being lengthwise of said carrier axis.

JOHN A. ZUBLIN.
